UNITED STATES PATENT OFFICE.

CHARLES T. DOUGHERTY, OF LEMOORE, CALIFORNIA, ASSIGNOR, BY DIRECT AND MESNE ASSIGNMENTS, OF SIX FIFTY-FIFTHS TO HATTIE E. DOUGHERTY, SIX FIFTY-FIFTHS TO E. H. DOUGHERTY, AND SIX FIFTY-FIFTHS TO F. C. DOUGHERTY, ALL OF HUNTINGTON BEACH, CALIFORNIA; SIX FIFTY-FIFTHS TO C. C. CAMPBELL, OF COALINGA, CALIFORNIA; SIX FIFTY-FIFTHS TO R. L. JOHNSTON, OF SANTA BARBARA, CALIFORNIA; THREE FIFTY-FIFTHS TO P. A. CAMPBELL, OF LONG BEACH, CALIFORNIA; THREE TWENTY-FIFTHS TO W. W. SMITH, TWO TWENTY-FIFTHS TO J. H. DUNAWAY, TWO TWENTY-FIFTHS TO RAY M. WAGNER, TWO TWENTY-FIFTHS TO CLARENCE WAGNER, AND ONE TWENTY-FIFTH TO ETHEL G. SMITH, ALL OF FRESNO COUNTY, CALIFORNIA.

OIL-WELL-TOOL OPERATOR.

Application filed December 3, 1923. Serial No. 678,371.

This invention relates to a tool for use in oil well drilling, and especially to a tool whereby other tools may be operated and whereby fishing operations and the like may be conducted.

In Coalinga, Bakersfield, and other California oil districts, it is found that the oil-bearing strata are located from two to four thousand feet below the ground surface.

10 The wells drilled are known as deep wells and are exceedingly costly, often requiring an expenditure of one hundred thousand dollars or more. When drilling these wells it is found impossible to reach any considerable depth with a single line of casing and it is therefore necessary to start with a large casing, for instance, 12½ inches, and proceed until this is landed, then continue with a 10 inch casing, and so on, the different sizes employed being usually 12½, 10, 8½, 6½ and 4½ inches. In other words, there may be four or five different strings of casing in a well.

25 Innumerable troubles are encountered in connection with carrying each string of casing to the furthest possible depth, among these may be mentioned, parting of the casing at different places by breakage of the casing, stripping of threads, etc., 30 freezing up of the casing, due to external friction or settling of sand, loss of tools, leaky joints, etc. Various forms of tools are employed for fishing out or removing a parted string of casing and lost tools, but 35 not always with success. Similarly, leaky joints may be tightened, but often causing damage to other joints, thereby necessitating removal of the casing and insertion of new sections. The failures encountered are 40 comparatively numerous and any number of abandoned wells may be found throughout the various oil districts; the work performed and the material lost in such instances representing an investment of millions of dollars. The main cause of failure 45 when loosening a frozen casing or removing

a parted casing is due to the fact that the tools employed are only capable of pulling out or lifting the casing as a whole. The upward pull or strain exerted under such conditions is enormous and sometimes causes parting of the casing again and again, or further loss of tools, thus rendering the operation of clearing the well increasingly difficult.

The purpose of the present invention is to provide a tool which is capable of more efficiently handling difficulties of this character and others, among which may be named the following:

1. Removing a frozen or lost casing, section by section.
2. Taking out broken pieces of casing.
3. Setting up leaky joints at any point desirable.
4. Setting up die collars or die nipples.
5. Disconnecting casing in case of water leaks.
6. Removing tools that are bull-dogged in the casing.
7. Locating joints where casing is cemented.
8. Taking out old casing to shut off water.
9. Unscrewing casing that is too rotten to stand strain from top of the hole.
10. Tightening joints at any place desired without tonging casing and spoiling joints in the string above.
11. Straightening up tools that are out of line with the casing so as to get them into the casing.
12. Removing a string, a piece at a time, or connecting up and removing as a whole, and in case of failure disconnecting at will and at place desired.
13. Connecting tool joints on lost tools or unscrewing the same.
14. The tool may also be employed for the purpose of rotating under-reamers of various makes and construction.
15. The tool may also be employed for the purpose of removing or attaching cut-

ting tools or bits of the type employed in connection with a rotating casing.

16. The tool may also be employed for the purpose of supporting a milling or cutting 5 tool, whereby obstructions in the casing or on tools lodged in the casing may be cut away.

The invention briefly stated comprises a ratchet block, a nut carried thereby, a spiral 10 shaft extending through the nut, means for imparting a reciprocal movement to the shaft, and means carried by the shaft capable of imparting a turning and a lifting movement.

15. The invention further consists of the parts and the construction, combination and arrangement of parts as hereinafter more fully described and claimed, having reference to the accompanying drawings, in which—

20. Fig. 1 is a section of a well showing the application of the invention.

Fig. 2 is a continuation view of Fig. 1, showing the position of the tool in the well and in engagement with the upper section 25 of a lost string of casing.

Fig. 3 shows a modified form of the tool.

Fig. 4 is a plan view of the ratchet block partly broken away.

Fig. 5 is a side elevation of the ratchet 30 block partly broken away.

Referring to the drawings in detail, A indicates a ratchet block of suitable length and diameter, on the exterior surface of which are mounted a plurality of gripping pawls 35 or ratchet members ². These pawls are pivotally mounted and are normally held in engaging position by springs indicated at 3. The pawls are provided for the purpose of locking the ratchet block against turning 40 movement within the well casing in one direction, and to release the block and permit turning movement thereof in the opposite direction. The ratchet block is preferably forged or otherwise formed from a single piece of steel as considerable strain is exerted thereon when the tool is in operation. Extending through the ratchet block from end to end, and centrally positioned therein, is a spiral shaped opening 4 through 45 which extends a spiral shaft 5. This shaft is provided with a collar at its opposite ends as at 6, which are provided for the purpose of limiting the stroke or reciprocal movement of the shaft with relation to the 50 ratchet block. Forming an extension of the lower end of the shaft 5 is a square shaft 7. This shaft is provided for the support of a tool holder and serves the function of imparting a turning movement and a lifting movement thereto.

To clearly illustrate one use of the tool, I will refer to Figs. 1 and 2. These figures represent a section of a deep oil well, the upper casing representing a common 8 65 inch casing as shown at 8, and the succeed-

ing casing a 6 inch casing as shown at 9. This last named casing has been lost in the well and is frozen therein, and in this particular instance is shown as located approximately two hundred feet below the lower end of the 8 inch casing. There are numerous fishing tools employed for the purpose of removing lost casing, among which may be named the following, spears, die collars and die nipples. These tools often prove a 75 failure due to the fact that they are only capable of one function, to-wit, that of exerting a pull or lifting a lost casing section as a whole. The upward pull or strain required under such conditions is often so great that the casing parts or the tools free themselves, and more than one well has been abandoned due to failure in this direction. The present tool is particularly suited for an instance of this character as it is capable 85 of entering the well and engaging the uppermost section of the lost casing and also capable of unscrewing the casing, section by section, and removing the same. This is, obviously a great advantage as comparatively no pull is required to remove the casing, section by section.

The tool proper forming the subject matter of this application is shown in Figs. 1 and 2. It is supported near the lower end 95 of the 8 inch casing by means of an inner casing as illustrated at 10, being connected with the ratchet block by means of a swivel connection as at 11. The casing 10 is merely provided for the purpose of supporting 100 the ratchet block and the swivel 11 to permit turning movement of the same in one direction, as will hereinafter be described.

Extending downwardly through the inner casing 10 is a drill line 12, and forming a 105 connection between the drill line and the spiral shaft 5 are a combination socket 14 of suitable construction, a set of jars 15, a stem 16 and a rope socket 17. These several connections are known as a string of tools and they serve several functions; the combination socket 14, that of making a connection with the shaft 5; the jars 15 that of transmitting a driving movement when required; the stem 16 that of adding weight to the 110 string of tools, and the rope socket that of connecting a string of tools with the drill line 12.

Suitably attached to the lower end of the ratchet block A is a swivel connection 18, and forming an extension thereof is a pipe 19, the lower end of which is closed by a turning block 20, said turning block being secured to the pipe 19 by screws 21, rivets or otherwise. The turning block is provided with a centrally disposed square opening 22 through which the shaft 7 extends, and it is provided for the purpose of transmitting 120 turning movement to a section of casing 23, which is suitably attached thereto as at 24, 125 130

the casing 23 being merely an extension of the tool and being provided for the purpose of supporting the tool required for the work in hand.

5 In the present instance, I have illustrated a standard form of spear as at 25. The spear is secured to the lower end of the casing 23 and is capable of two functions, that of entering the upper end of the lost casing 10 and engaging the same, and secondly, that of unscrewing the casing and removing it. This is accomplished in the following manner:

With the tool in position in the well as 15 illustrated in Figs. 1 and 2, it is only necessary to transmit a reciprocal movement to the string of tools shown in Fig. 1. This may be accomplished by fastening the drill line to a walking beam or by passing it over 20 a bull wheel. This reciprocal movement is of course transmitted to the shaft 5 and as it passes through the nut or spiral shaped opening formed in the ratchet block A, it is obvious that a turning movement will be 25 transmitted thereto when travelling in an upward direction, this being due to the fact that the pawls engage the interior of the 8 inch casing and thereby secure the ratchet block against turning movement. The turning 30 movement of the shaft 5 is also transmitted to the square shaft 7 forming an extension thereof, and through the block 20 turning movement is also transmitted to the casing 23 and the spear 25 carried thereby. The first upward movement of the 35 shaft causes the expanding slips 26 on the spear to grip the upper end of the lost casing, and still further movement, after the grip has been made, causes a turning movement to be transmitted to the upper section 40 of the casing 9, thereby unscrewing it with relation to the collar 27. The spiral in the shaft 5 is so arranged that approximately only one revolution is transmitted during 45 the upward travel of the same, and as it takes several turns of the casing to unscrew the same, it is obvious that shaft 5 must be raised and lowered from 10 to 30 times before the pipe is entirely free.

50 The ratchet block transmits a turning movement to the spiral shaft when this is moved in an upward direction and the spiral shaft in turn transmits a turning movement to the ratchet block when travelling in a downward direction, this being due to the 55 fact that swivel joints, as at 11 and 18, are connected with the opposite ends of the ratchet block, and also due to the fact that the pawls 2 will only secure the ratchet block against turning movement in one direction. This is of importance as it is necessary that a turning movement should be transmitted to the engaging tool, for instance, the spear 25 only in one direction.

60 When a casing section is unscrewed it is re-

moved by lifting the entire mechanism out of the well, and then re-inserting the same and proceeding as described.

The foregoing is a brief description of the operation of the tool, or the function of the same under normal conditions. It may, however, happen that the threads of the casing 9 have been set up or so tightly screwed that a slow upward pull or movement of the shaft 5 would not loosen the same. The jars 15 are then brought into function by attaching the drill line to a walking beam. This exerts a quick upward pull on the string of tools and thereby transmits a driving action through the medium of the jars, which is more than sufficient to start any thread.

From the foregoing it can be seen that a lost casing may be unscrewed, section by section, and thus removed, and similarly that several sections may be unscrewed in unison if desired. This is, obviously, a great advantage over other tools which are only capable of pulling out the casing as a whole as they often prove a failure. The present tool would not be a failure under these conditions as it would only have to remove one or more sections of the casing at a time. As stated in the preamble of the specification, the tool is capable of many functions, that of unscrewing and removing pipe sections as described; setting up leaky joints at any point desired; setting up die collars or die nipples; disconnecting casing in case of water leaks; removing tools that are bull-dogged in the casing; taking out old sections of casing, etc.

A tool such as illustrated in Figs. 1 and 2 is capable of most of the requirements specified, but only under certain conditions, and I therefore provide a modified form of the tool as shown in Fig. 3, this form being particularly adapted for tightening up or unscrewing casing sections at any depth desired. This tool is lowered into the well by a drill line and string of tools such as shown in Fig. 1, and it is held at any point desired by frictional engagement of spring arms such as indicated at 30. Two ratchet blocks are employed as at 31 and 32. Both are identical in construction to that shown in Figs. 2 and 4, one forming the function of a holder, and the other function of a wrench when tightening or unscrewing casing sections. When tightening up sections the tool assumes the position shown in Fig. 3, and when unscrewing casing sections, it is only necessary to reverse the position of the tool end for end as turning movement will then be transmitted in opposite directions, or it is obvious that reversible pawls might be employed to avoid turning of the tool end for end.

The tool shown in Fig. 3, as already stated, is particularly adapted for setting up or un-

screwing casing sections, the tool being capable of this operation even though one casing is mounted within the other. For instance, the upper ratchet block might engage the inner face of an 8 inch casing, and the lower ratchet block might be reduced in diameter to enter a 6 inch casing. In that case, the upper ratchet block will serve as a holder whether the 6 inch casing was being tightened up or removed.

The tool is capable of many other uses, for instance, that of lining up lost tools with the end of a casing. It sometimes happens that a drill bit becomes unscrewed or detached with relation to a string of tools. If this should happen, it is only necessary to attach a tool, known as a "ram horn", to the end of the square shaft 7 and then lower the tool to the bottom of the well. A slight upward pull of the shaft 5 will then transmit a turning movement to the shaft section 7 and the ram horn tool attached thereto. This would cause the ram horn to engage the drill bit and swing it into alignment with the casing. It will thus render it possible to lower an ordinary combination socket to engage and remove the bit.

The important feature of the present invention is the fact that I have provided a tool which is capable of transmitting, first of all, a turning movement, secondly, a lifting movement, and third, a driving movement. These movements combined permit attachment and use of varying forms of tools, and permit handling of these tools in a manner heretofore never attempted.

While certain features of the present invention are more or less specifically illustrated, I wish it understood that changes in design and construction may be resorted to within the scope of the appended claims. I similarly wish it understood that the materials and finish of the several parts employed may be such as the experience and judgment of the manufacturer may dictate or varying conditions may demand.

Having thus described my invention, what I claim and desire to secure by Letters Patent is—

50. 1. A tool of the character described comprising a ratchet block, a plurality of pawls pivotally mounted in the ratchet block engageable with the interior wall of a well casing to secure the ratchet block against turning movement in one direction, a nut formed within the ratchet block, a helically twisted shaft extending through the nut and slideable therein, a swivel connection below the ratchet block, a tool holder attached to the swivel connection, means for transmitting a turning movement from the helically twisted shaft to the tool holder and the swivel connection, said means comprising a square shaft forming an extension of the helically twisted shaft and extending down

into the tool holder, and a nut in the tool holder through which the square shaft extends.

2. A tool of the character described comprising a nut, a threaded shaft extending through the nut, and slideable and turnable in the nut, means for supporting the nut at a predetermined point within a well casing, and means on the nut engageable with the well casing to secure the nut against turning movement when the shaft travels in one direction to transmit a turning movement to the shaft, said means adapted to release the nut to permit this to turn within the well casing when the shaft moves in the opposite direction.

3. A tool of the character described comprising a nut, a threaded shaft extending through the nut and slideable and turnable therein, means for supporting the nut at a predetermined point within a well casing, means on the nut engageable with the well casing to secure the nut against turning movement when the shaft travels in one direction to transmit a turning movement to the shaft, said means adapted to release the nut to permit this to turn within the well casing when the shaft moves in the opposite direction, a tool holder carried by the shaft, and means for transmitting a turning movement from the shaft to the tool holder.

4. A tool of the character described comprising a ratchet block, a plurality of pawls pivotally mounted in the ratchet block engageable with the interior wall of a well casing to secure the ratchet block against turning movement in one direction, a nut formed in the ratchet block, a helically twisted shaft extending therethrough, and slideable and turnable therein, and a tool holder carried by the shaft adapted to be turned thereby.

5. A tool of the character described comprising a ratchet block, a plurality of pawls pivotally mounted in the ratchet block engageable with the interior wall of a well casing to secure the ratchet block against turning movement in one direction, a nut formed in the ratchet block, a helically twisted shaft extending therethrough and slideable and turnable therein, independent means for supporting the ratchet block at a predetermined point within the casing, a tool holder supported by the shaft, and means for transmitting a turning movement thereto.

6. A tool of the character described comprising a ratchet block, a plurality of pawls pivotally mounted in the ratchet block engageable with the interior wall of a well casing to secure the ratchet block against turning movement in one direction, a nut formed in the ratchet block, a helically twisted shaft extending therethrough and slideable and turnable therein, means for supporting the ratchet block at a predetermined point with-

in a well casing, a swivel connection between the ratchet block and said support, a second swivel connection attached to the lower side of the ratchet block, a tool holder attached 5 to the swivel connection, and means for transmitting a turning movement from the shaft to the tool holder and the swivel connection.

7. In a tool of the character described, a nut, means for supporting the nut against vertical movement within a well casing, means carried by the nut and engageable with the interior surface of the well casing to secure the nut against rotation in one direction, a helically twisted shaft extending through 15 the nut, means for imparting a reciprocal movement to the shaft which movement is simultaneously transmitted to rotary movement by the nut and the helical formation of the shaft, and a tool adapted to be rotated by 20 said shaft.

8. The combination with a well casing, of a fishing wrench therefor, said wrench comprising a ratchet block, pawls on said block locking the block against turning movement 25 in one direction within the casing, a second casing adapted to support the ratchet block

at a predetermined point within the first named casing, a swivel connection between the second named casing and the ratchet block, a nut formed in the ratchet block, a 30 helically twisted shaft slidable and turnable in the nut, and a tool holder adjacent the ratchet block and below the same adapted to be turned by the shaft.

9. The combination with a well casing, of 35 a fishing wrench therefor, said wrench comprising a ratchet block, pawls on said block locking the block against turning movement in one direction within the casing, a second casing adapted to support the ratchet block 40 at a predetermined point within the first named casing, a swivel connection between the second named casing and the ratchet block, a nut formed in the ratchet block, a helically twisted shaft slidable and turnable 45 in the nut, a swivel connection attached to the lower side of the ratchet block, a tool holder carried thereby, and means for transmitting a turning movement from the shaft to the swivel and the tool holder carried 50 thereby.

CHARLES T. DOUGHERTY.
